UNITED STATES PATENT OFFICE.

SAMUEL T. BOLE, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

GUARD-RAIL FOR PASSENGER-CARS.

No. 902,368.

Specification of Letters Patent. Patented Oct. 27, 1908.

Application filed August 18, 1908. Serial No. 449,135.

To all whom it may concern:

Be it known that I, SAMUEL T. BOLE, a citizen of the United States, residing in Philadelphia, Pennsylvania, have invented 5 certain Improvements in Guard-Rails for Passenger-Cars, of which the following is a specification.

My invention relates to certain improvements in guard rails which are mounted on 10 the platform end of a passenger car, particularly of the type of car in which the passenger pays the fare on entering the car, the guard rail separating the ingress passageway from the egress passageway.

15 The object of my invention is to make the guard rail movable vertically and so construct the guard that it can be lowered in position to separate the platform into two sections, or be raised so as to provide an uninterrupted passageway.

In the accompanying drawings:—Figure 1, is a sectional plan view of the platform end of a passenger car illustrating my invention, the guard rail being lowered so as to 20 divide the platform into ingress and egress passageways; Fig. 2, is a longitudinal sectional view on the line 2—2, Fig. 1, showing the rail in its lowered position; Fig. 3, is a view illustrating the upper portion of the car 25 showing the rail in its raised position; Fig. 4, is a detached view showing one of the posts supporting the rail; and Fig. 5, is a view of a modification, showing the rail lowered to a position below the floor to provide an uninterrupted passageway.

30 In the accompanying drawing A is the platform of a passenger car, B is the body of the car, and in the partition separating the body of the car from the platform is an ingress passageway b, and an egress passageway b', in the present instance separated by a post b².

35 a is the vestibule framing closing the front of the car, and of the usual form. On one 40 side of the car is a panel a', and a sliding door a² which is adapted to enter a slideway in the panel, so that when the platform is at the rear of the car, that side of the car is entirely closed, the other side being open, and 45 when the platform is at the forward end of the car the door can be operated to allow for the exit of passengers only. The opposite 50 side of the front platform is open and may be

closed by either a door or a movable railing, as desired.

55 D is a rail dividing the platform into two sections, i² being the ingress section, and i' the egress section, communicating respectively with the passageways b, b', in the partition separating the body of the car from the platform.

60 E, E', E², are three vertical posts extending from the floor of the platform to the roof of the car, or terminating at a point sufficiently near the roof to allow headroom for 65 passengers. The rail D is adapted to these several posts, and is free to be moved vertically thereon.

70 In the present instance I have shown stops e on each post in the form of rivets which limit the downward movement of the rail, so that its lowest position will be about the height of the waist of the passenger, and the rail can be moved vertically on these posts until it assumes the position shown in Fig. 75 3, and it is held in this position by a catch, in the present instance in the form of a pivoted pawl e' on the post E, the pawl holding the rail at a point sufficiently above the platform to allow headroom for the passengers 80 to pass to and fro underneath it. I have found one catch sufficient to retain the rail in its raised position, although a catch may be mounted on each post.

85 The rail D in the present instance, consists of a bent section d coupled at one end to a head d' and at the opposite end to a coupling d² adapted to the posts E' and E respectively, and secured to the coupling d² is a section d³ which is also attached to a 90 head d⁴ adapted to the post E², but it will be understood that the details of the construction of the rail may be modified without departing from the essential features of the invention.

95 In some instances, in place of raising the rail so as to be above the heads of the passengers when it is desired to move it out of service, it may be lowered into a recess in the floor of the platform, as shown in Fig. 100 5, and covered with a movable cover plate or board, if desired, and in this case the catches e² will be substituted for the stops e. In this construction it may not be necessary to extend the posts to the roof, but only to 105 the height of the rail, when elevated. Thus

it will be seen that when it is desired to divide the platform into ingress and egress passageways, the rail is placed in the position as shown in Figs. 1 and 2, and this is particularly so when the platform is at the rear end of the car, but if the platform is at the forward end of the car, and it is desirable that there shall be an uninterrupted passageway at the forward end, then the rail can be raised to the position shown in Fig. 3, if the construction shown in that figure is used, or it may be depressed, as shown in Fig. 5, so as to give a clear space for the egress of passengers at the forward end of the car, or to allow room for seats, if desired.

I claim:—

1. The combination in a passenger car, of a platform, a guard rail mounted above the platform and so dividing it as to form ingress and egress passageways, said guard rail being capable of being raised or lowered bodily into or out of position.
2. The combination in a passenger car, of a series of vertical posts, a guard rail vertically adjustable on said posts, and means

for holding the guard rail in position to divide the platform into separate passageways.

3. The combination of a platform of a passenger car, a series of vertical posts, a guard rail adapted to slide vertically on said posts, means for retaining the guard rail in position about the waist line of a passenger, and means for retaining it in its raised position so as to provide an unobstructed passageway.

4. The combination of the platform of a passenger car, a series of posts, a guard rail when in one position dividing the platform into ingress and egress passageways, stops to limit the downward movement of the rail, and a catch adapted to retain the rail in its raised position.

In testimony whereof, I have signed my name to this specification, in the presence of two subscribing witnesses.

SAMUEL T. BOLE.
